UNITED STATES PATENT OFFICE.

EDWARD E. BEATY, OF SEATTLE, WASHINGTON.

CUTTER HEAD.

Application filed October 7, 1926. Serial No. 140,038.

This invention relates to cutter heads for wood-planing machines; and its object, generally, is the perfecting of heads of this character, and particularly to the manner 5 or means for mounting the cutter knives adjustably to the body of the head.

More specific objects and advantages of the invention will appear in the following specification.

10 The invention consists in the novel construction, adaptation and combination of parts hereinafter described and claimed.

In the accompanying drawing,—

Figure 1 is a fragmentary side elevational view of a cutter head embodying the present invention; Fig. 2 is a detail sectional view on broken line 2—2 of Fig. 1; Fig. 3 is a sectional view on line 3—3 of Fig. 2 and including the arbor for the head; Fig. 4 is 20 a perspective view of the head body; and Fig. 5 is a transverse sectional view of one of the cutter knives.

As shown in said drawing, the cutter head proper comprises a cylindrical body 10 having intermediate its length a peripheral channel 11 to provide a hub portion 12 and relatively wide and narrow flange portions 13 and 14, respectively, at its opposite ends.

Said body flanges are provided with pluralities of cylindrical bores 15 and 16 which are arranged in axially aligned pairs, the complementary bores of each pair being disposed—one in each flange—circumferentially about and parallel with the axis of the arbor 35 17 which carries the head.

18 and 19 represent cutters of the circular type which, in the present invention, are located between the flanges 13 and 14 and are mounted upon bolts 20 which extend 40 through holes 21 provided eccentrically in cylindrical bushings 22 and 23 fitting within the respective bores 15 and 16. These bushings are secured against rotary movement relative to the head by means of splines 24 45 connected to the bushings engaging in key ways 25 of the head. The rotary positions of the complementary bushings being such that the eccentrically disposed bolt receiving holes thereof are located in relatively 50 close proximity to the peripheries of the respective flanges so that the respective bushings will provide relatively large end surfaces to serve as bearings against the associated cutter at diametrically opposite side 55 of the latter with respect to the cutters cutting edges.

The inner ends 26 of the bushings 22 and 23 are, moreover, each disposed in a plane inclined from a plane at right angles to the axis of the respective bushings such that bearing surfaces will be provided for the side surfaces, as 27, of the cutters to maintain the latter in similarly inclined planes with respect to the associated bushing and bolt axes so as to afford side clearance to a 60 cutter. Where a bolt has mounted thereon more than one cutter, as 19 for example, a spacer 28 is interposed between the cutters. Such a spacer has both of its ends 26' inclined with respect to planes at right angles 65 to the axis of the spacer. To prevent rotation of the spacer 28 relative to the bushings 22 and 23, the bolts 20 pertaining thereto are each provided with spline elements 40 to engage in a key way 41 provided in 70 the respective bushing.

To accommodate the cutters to the inclination of the bushing and spacer ends 26 and 26', said cutters are each provided with a tapering hole 30, see Figs. 3 and 5, to receive the respective bolt 20.

The bolts 20 serve to rigidly unite the respective cutters and bushings, and also with the spacers where used, and for which purpose each bolt is provided with a head 20' 80 to engage against the bushing 22 at one end of an assembly of cutters and bushings, preferably in a recess provided in the referred to bushings and screw threading the bolt to receive a nut 20² to engage against the bushing 23 at the other end of an assembly.

An assembly thus united is movable axially as a whole to adjust the lateral position of the respective cutter, or cutters, as by means of an adjustment screw 31 (Fig. 3) engaging 95 in a screw threaded hole 32. Said screw 31 has integral therewith a collar element 33 which engages in a transverse slot 34 provided in one of the bushings 22 or 23 of the respective assembly.

The collar 33 advantageously operates within a recess 35 of the head. After the cutters are regulated longitudinally of the head by means of the respective adjustment screws 31, as above explained, the same may be secured in such positions, as shown in Figs. 1 and 2, by means of set screws 36, one for each cutter and bushing assembly, extending through screw threaded holes 37 of the flange to engage against plane surfaces 38 provided upon the respective bushings 22.

What I claim, is:—

1. In a cutter head having two spaced apart peripheral flange elements provided with cylindrical bores having their axes aligned with each other and parallel with the axis of the head, an apertured cutter located between said flange elements, a bolt extending through the aperture of said cutter, bushings provided for said bolt within the respective flange bores, and means cooperating with the bolt for securing the bushing in operative relation with respect to said cutter.
2. In a cutter head as defined in claim 1 in which means engageable with one of the head flanges is utilized to effect adjustments of the cutter in either direction selectively parallel with the axis of the head.
3. In a cutter head as defined in claim 1 in which the cutter is rotatably adjustable upon the bolt, and the bushings are secured to the respective flanges against rotary movement.
4. In a cutter head as defined in claim 1 in which the cutter is arranged for rotary adjustments upon the bolt, and means connecting the bushings to the respective head-flanges, said means preventing rotary movement of the bushings and permitting axial movement thereof to effect lateral adjustments of the cutter.
5. In a cutter head as defined in claim 1, in which the bolt is disposed eccentrically of the bushings therefor.
6. In a cutter head as defined in claim 1

in which the cutter aperture is tapered to provide seating surfaces against diametrically opposite sides of the bolt when the cutter is inclined from a plane at right angles to the bolt axis at all rotary adjustments of the cutter.

7. In a cutter head as defined in claim 1 in which the bushings are provided with end surfaces engageable with the cutter for retaining the latter in a plane inclined relation to the axes of the bolt and head respectively.

8. In a cutter head provided with two peripheral flange elements, said flange elements being provided with a plurality of circumferentially spaced apart bores having their axes parallel with the axis of the head, the bores of one of said flanges being in axial alignment with the respective bores of the other flange, a circular cutter, a bolt adapted to extend through said bores and the cutter for supporting the latter, said bolt being arranged parallel with the axis of the head, means mounted upon the bolt and engageable with the cutter for securing the cutter to the bolt in inclined relation with respect to a plane at right angles to the axis of the bolt, and means acting through the medium of the aforesaid means for regulating the position of the cutter longitudinally of the head.

Signed at Seattle, Washington, this 17th day of September, 1926.

EDWARD E. BEATY
